PLASTIC SKIRTING-BOARDS
Heinrich Grün, Lindenstrasse 34, Dusseldorf, Germany
Filed May 31, 1961, Ser. No. 113,834
1 Claim. (Cl. 52—287)

Skirting boards made from plastic substance are known and being introduced in practice to an ever-increasing extent.

The skirting boards hitherto known have, however, very serious imperfections due chiefly to the manner in which they are secured to the wall.

If the skirting boards are fixed on the wall by nails passing through them, the nails visible from the outer side detract from the appearance. Moreover, the holes in the skirting board caused by driving in the nails become larger in the course of time, thereby affecting the firm hold of the skirting board on the wall. The danger of the nails rusting, due to the moisture coming into contact with them when washing the floor, is another objection.

If the skirting boards are stuck on the wall, the objection arises that this method of fixation is unreliable and the plaster peels off the wall with the board.

Fixing the skirting boards in the wall with gypsum by means of a dovetail projection provided on the side of the skirting board facing the wall, is relatively expensive. In the course of time the gypsum rots and crumbles out with the result that the skirting board loses its hold.

Forms of construction of plastic skirting boards are also known in which a metal strip is provided for fixing to the wall. This metal strip is secured in position by means of nails. Such skirting boards are, however, relatively expensive. Moreover the metal strip makes the skirting board conspicuous and detracts from its appearance.

Another objection to the known skirting boards consists in that the moisture creeping downwards in the plaster causes the skirting board to buckle so that it is forced away from the wall.

According to the invention a fixing member separate from and covered by the skirting board is provided in the wall and the skirting board has on the side facing the wall a projection adapted to resiliently engage this fixing member with a clamping fit. As a result the skirting board can be reliably and firmly fitted in position and is nevertheless removable and exchangeable without using any fixing means passing through the skirting board.

The construction may be such that on the side of the skirting board facing the wall a hollow channel is provided having a slot extending in longitudinal direction along the apex of the channel and preferably formed by flaps or tongues standing out from this side of the board. In the wall holding means are arranged having a head penetrating through the slot into the hollow channel and engaging behind the edges of the side walls of the slot. This practical form of construction allows the skirting board to be made in the conventional manner by pressing. The elasticity of the walls of the hollow channel causes the skirting board to be pressed against the wall when it is being fitted.

The side walls of the slot are preferably bent over into the hollow channel like tongues which project into the hollow channel. Thus the firm seating of the skirting board on the holding means is increased and the bracing against the wall can be very strong.

Pins or nails with a conical head the base surface of which is directed towards the shank, can be driven into the wall as holding means. It is evident that the nail head can also be bulged in the direction of the axis of the cone or unround, also of angular cross-section.

It is also possible to construct the head of the pin or

2

nail like a press-button and to make it, for example, in the shape of two cones the bases of which face each other.

A groove-like recess is preferably provided in the wall in which the fixing means fixed on the wall are accommodated and which receives the hollow channel formed by the two tongues or flaps on the skirting board. In this manner the fixing of the skirting board on the wall does not make the skirting board conspicuous or add to the distance which it stands out or projects from the wall.

10 Another form of construction according to the invention consists in that a projecting longitudinal rib is provided on the side of the skirting board facing the wall and a counter projection or counter rib on the wall, the two projections or ribs being constructed to interengage.

15 The rib on the rear side of the skirting board may be inclined towards the edge of the skirting board remote from the floor and the rib provided on the wall may slope in the opposite direction. In this case the rib on the skirting board will, so-to-speak, snap into the rib on the wall when the skirting board is fitted in position.

20 The wall rib may be formed by suitably shaping a flat strip, for example of sheet metal, fixed on the wall by means of pins or nails.

25 It is advisable to provide on the side of the skirting board facing the wall a rib on each side of the fixing rib to support the skirting board against the wall.

30 It is particularly advantageous to provide a pocket on the bottom edge of the skirting board facing the floor for example for receiving the edge of a floor covering. This ensures a neat close fitting and durable joint between the skirting board and the floor and does not allow water to penetrate behind the skirting board when the floor is being washed.

35 Another possibility is to arrange in this edge pocket an elastic strip bearing under pressure against the floor or the floor covering. It is evidently also possible to fit this flat strip in some other way.

Two embodiments of the invention are illustrated by way of example in the accompanying drawing, in which

40 FIG. 1 is a perspective view of the first embodiment,
FIG. 2 a modified form of construction of the fixing means employed in the first embodiment, and

FIG. 3 a perspective view of the second embodiment.

45 1 designates the skirting board made from plastic substance, for example plastic based on polyvinyl chloride, with a certain amount of elasticity. It has a curved cross-section with an edge projecting from the wall and resting on the floor.

50 According to FIG. 1 the skirting board has on its side facing the wall two flaps or tongues 2 which together form a hollow channel 3 with a longitudinal slot along its apex or deepest point. The free ends or edges 4 of the flaps or tongues are folded over into the hollow channel into which they project. The wall 17 has a groove-like recess 5. Pins or nails 6 are driven into the wall at the bottom of this recess. These pins or nails have a head 7 in the form of a cone with its base facing the shank. The hollow channel of the skirting board fixing means is slipped over the nails through the intermediary of the slit so that the heads of the nails pass through the slot into the interior of the hollow channel, as can be seen from FIG. 1. The hollow channel is then in the recess 5 below the surface of the wall.

55 65 The nails may be provided with heads having the shape shown in FIG. 2, that is in the form of two cones with their bases bearing one against the other or having a common base.

70 The edge of the skirting board adjacent the floor has a pocket 8 into which the edge of the floor covering 9 is inserted. The pocket comprises a pair of spaced, parallel, flexible arms joined by a bight portion, one of

the arms being integrally joined at the lower terminal edge of the board. The other arm has a free terminal edge engaging the floor. The arms form an acute angle to the plane of the board. The arms and bight form a pocket for receiving a terminal edge of a strip of covering material whereby the terminal edge of the board is in contact with the strip and urges the strip into pressure engagement with the floor.

In the example illustrated in FIG. 3 the skirting board 1 has on the side facing the wall a rib 10 which slopes towards the edge of the skirting board remote from the floor. A sheet metal strip 11 is fixed on the wall by means of pins or nails 12. The edge of the strip remote from the floor is shaped to form a rib 13 sloping in the opposite direction to the rib 10. When fitting the skirting board in position the rib 10 snaps into the rib 13. Longitudinal ribs 14 are also provided one on each side of the rib 10 and bear against the wall or the sheet metal strip 11 fixed thereon. The edge of the skirting board directed towards the floor is shaped to form a pocket 15 in which an elastic packing strip 16 is inserted, the free end of which bears against the floor or the floor covering.

I claim:

A skirting board of plastic material having longitudinal top and bottom flanges projecting from the same side of said board for bearing against a wall surface and a floor surface, said board further including a pair of integral spaced walls extending longitudinally intermediate said top and bottom flanges and directed generally perpendicularly away from said board in the same direction as said flanges said spaced walls having reversely curved outer ends providing resiliently deformable longitudinal wall portions facing each other and defining a slot for receiving fastening elements having a headed part of a larger size than said slot and for locking behind said

headed part, said bottom flange comprising a pair of spaced, flexible arms joined by a bight portion, one of said arms being integrally joined at an edge to a terminal edge of said board, said bight portion being spaced from said board, the other arm having a free terminal edge, said arms being substantially parallel to each other and at an acute angle to the plane of said board, said arms and bight portion forming a pocket for receiving the terminal edge of a strip of covering material whereby the terminal edge of said board is in contact with the strip and urges the strip into pressure engagement with the floor.
